PAINTER'S EQUIPMENT

William R. Van Winkle, Madisonville, Ohio

Application June 11, 1936, Serial No. 84,632

3 Claims. (Cl. 91—66)

The present invention relates to painter's equipment and particularly to such as may be used by painters engaged commercially in the painting trade.

5 An object of the invention is to provide an arrangement of means whereby a painter may save considerable time and effort on painting jobs.

Another object of the invention is to provide means whereby a painter is enabled to complete 10 a large painting job at less expense than heretofore, and with less bodily fatigue, so that the job may be uniformly high grade from start to finish.

Another object of the invention is to provide 15 durable, inexpensive, and simple means for accomplishing the above objects.

The foregoing and other objects are attained by the means described herein and disclosed in the accompanying drawing, in which:

20 Fig. 1 is an elevational view of a complete painter's apparatus embodying the present invention.

Fig. 2 is an enlarged cross-sectional view taken on line 2—2 of Fig. 1.

25 Fig. 3 is an enlarged fragmental cross-sectional view taken on line 3—3 of Fig. 1.

Fig. 4 is a perspective view of a modified form of reservoir applicable to the Fig. 1 combination.

30 Fig. 5 is a perspective view of a modified form of painter's apparatus embodying the invention.

Prior to the present invention, it was customary for painters to use the same or similar cans in which paint was supplied by the manufacturer, as a receptacle into which the brush was dipped 35 during the process of painting. This can or bucket was either hung upon a ladder rung by means of a hook, or placed upon the scaffold or any other available supporting means, in the vicinity of the work to be painted. It was always necessary to move the can or bucket from 40 place to place as the work progressed, and to stoop or bend over in order to dip the brush at intervals in order to replenish the supply of paint on the brush. The stooping and bending is perhaps the most fatiguing part of the painter's 45 work, and the extra effort thereby made, necessarily resulted in a considerable waste of time and extreme fatigue before completion of the job.

Moreover, frequent movement of the paint can or bucket to various locations on the job resulted in spilling of the paint or the application 50 of paint rings, from the bottom of the bucket, to surfaces not intended to be painted. All of the 55 objections mentioned above have been obviated

by the present invention, which will now be described and explained in detail.

In Fig. 1, the character 12 indicates generally a rack or harness adapted to be carried upon the back of the painter, and to support a reservoir 5 13 for paint or other liquid suitable for coating surfaces to be decorated or refinished. It is intended that the term "paint" as used herein, shall include generally any liquids or preservatives that may be applied to a surface to be coated 10 or treated. The rack or harness comprises a pair of uprights 14 and 15 of any suitable material, preferably strap metal, suitably connected together by any form of bracing means 16. The upper ends of the uprights are developed into 15 hooks 17 for supporting the rack or harness upon the shoulders of the user. Suitable means are provided for securing the rack or harness to the user's body, which means may conveniently be provided in the form of body straps 18 and 19 20 adapted to encircle the chest or waist of the user. At the lower ends of the uprights, the rack is provided with supporting means for the reservoir 13, one form of supporting means being indicated and illustrated as horizontal rearwardly extended 25 arms 20, properly spaced and proportioned to support the reservoir. The reservoir may be held in place upon the support means 20 in any suitable manner, such as by means of a strap or band 21. The rack or harness is of such length and 30 proportions that the paint or other treating substance in the reservoir may gravitate to a brush cup or receptacle 22 in a manner to be described.

The brush cup or receptacle 22 may be of metal or other suitable material of a depth approximating the length of the bristles of a brush, or perhaps slightly in excess thereof, so that a brush may be placed therein with the handle extending upwardly, and be supported in such position when the brush is not in actual use. The brush 35 cup or receptacle preferably is tapered toward the bottom wall 23 thereof, the mouth 24 being somewhat larger than the bottom. The receptacle may be of metal or other suitable material, and it is preferably provided with a reinforcing 40 bead 25 at the mouth or upper edges thereof.

Means are provided for charging the cup or receptacle with paint or the like contained within the reservoir 13. Said means may be in the form of a charging nozzle 26 arranged to direct the 50 paint onto the bottom of the receptacle, the flow of paint being regulatable by any accepted form of valve or stop cock 27. The valve or stop cock is placed in fluid communication with the bottom 55 of the reservoir 13 by means of a flexible tube or

hose 28 of any desired form. The paint is adapted to be fed by gravity from the reservoir 13 to the receptacle or cup 22, and to be controlled by the valve 21, the valve being accessible 5 at all times.

It will be understood that the brush cup or receptacle 22 may be manufactured in various forms, the form illustrated being exemplary only. With reference to Fig. 2, it will be noted 10 that the rear wall 29 of the receptacle carries one or more hooks or supporting means 30 whereby the receptacle may be hung upon the clothing of the painter, or upon a suitable belt or the like worn about his waist or limbs. Extending from 15 the receptacle is a member 31 which carries one or more hooks 32 similar to the hook 30 and adapted likewise to engage a belt or other support means worn by the painter. The extended member 31, together with the hook means 32 20 provide a handle for the brush cup or receptacle in the event that it is desired to detach the assembly from the person and to hold it in one hand while using the brush in the other hand. Such use of the brush cup or receptacle may be 25 desirable under certain circumstances. It will be understood, of course, that the hooks 32 are preferably integral with the extension 31, and are arranged at the level of the hook 30 on the 30 back of the receptacle. The hook 30 may be integral with a downwardly extended strap 33 of metal or the like which may be riveted or otherwise suitably secured to the rear wall of the cup or receptacle as indicated at 34.

The brush cup or receptacle may include a 35 means for squeezing and/or holding a brush placed upright within the receptacle, such means being operable by hand and adapted for fixation while embracing a brush to be held within the receptacle or cup. The squeezing and holding 40 means may consist of a pair of bell cranks or levers 35 and 36 connected together at their upper ends by means of a rod or wire 37 which is so located as to cooperate with the forward upper edge 38 in squeezing the bristles or clamping 45 the body of a brush placed within the receptacle and between the members 37 and 38. The lower ends of the bell cranks preferably are connected together by means of a transverse portion 39 which carries a depending latch piece or tongue 50 40. The latch piece or tongue is adapted to be engaged, at the will of the user, by a keeper or cooperative latch piece 41 which may be pivotally or otherwise mounted at the lower end 42 of the hook strap 33. In other words, movement of 55 the keeper or latch piece 41 to the dotted line position indicated in Fig. 2, serves to limit counter-clockwise rotation of the bell cranks about their common shaft 43, which shaft is journaled upon the rear wall 29, in one or more bearings 60 44. The bearing as shown in the drawing, is an integral part of the hook strap 35, but in practice, suitable bearings for the brush squeezer and holder may be in the form of individual hinge leaves fixed directly upon the receptacle wall. The inherent resiliency of the various parts of the brush squeezer and holder may be depended upon 65 for the accommodation of various thicknesses of brush bodies between the elements 37 and 38, when it is desirable to clamp a brush therebetween, or to squeeze paint from the bristles of the brush. The connecting piece or rod 37 normally serves the function of providing a ledge, 70 separate from the bead at 38 of Fig. 2, over which the brush may be traversed when it is desired to 75 merely remove excess paint from the brush, but

not to squeeze a substantial amount of paint from the bristles. It will be noted that the bar or rod 37, which is, in effect, a scraper for the bristles of a paint brush, is substantially uniformly spaced from the bead or upper edge 38 of 5 the receptacle, so that excess paint may be removed from the bristles without having the paint to drip from the bead 38 exteriorly of the receptacle. When a brush is to be held between the parts 37 and 38, the lower end of the hook strap 33 may be bent either forwardly or rearwardly to secure a proper spacing at 37-38 for any given brush, when the latch piece or keeper 41 is moved to the dotted line position.

In Fig. 3 is disclosed an adapter which may be 15 used for connecting the flexible hose or tube 28 to a paint can of any ordinary size or capacity. The adapter preferably is in the form of a funnel 45 having a suitable hose coupling at its lower constricted end 47, and an outwardly extended 20 annular flange 48 at its top. The flange is suitably apertured as at 49 to receive a plurality of screws 50 having wing nuts 51 applied thereto, said screws passing through an interior metallic ring 52 and an annular gasket 53, between which 25 ring and gasket is disposed the lid 54 of an ordinary paint can. The upper annular flange of the funnel member is of a diameter such that the funnel member will fit the lid of a small paint can, for example, that of a quart can. The 30 adapter will also fit the lids of larger cans, as will be understood, it being necessary only to punch holes in the lid to coincide with the holes of the adapter flange, for reception of the screws 50. After application of the adapter to a lid, the 35 central portion of the lid may be broken away or punched downwardly into the adapter funnel, as indicated at 55. The can thus connected with the 40 flexible hose 28, may then be fastened to the rack or harness 12.

In Fig. 4 is disclosed a modified form of paint reservoir, which comprises a substantially flat tank 56 having a lid 57 that may be removed when it is desired to pour paint into the tank. The bottom wall of the tank has an outlet pipe 45 or nipple 58 adapted to have connection with a coupling 59 on the hose 28, for conveying paint from the tank to a brush cup or receptacle such as was described in connection with Figs. 1 and 2. The back of the tank 56 has mounted thereon 50 the bands or straps 60 and 61 whereby the tank may be applied either to the back or at the front of the user of the device. By means of the construction disclosed in Fig. 4, the rack or harness shown in Fig. 1 may be eliminated.

The Fig. 5 modification differs from the device of Figs. 1 and 4, in that the brush cup or receptacle 62 is integral with, or attached to, the tank 63. The bottom wall 64 of the tank or reservoir 63 is provided with a valve or stop cock 65 which has a nozzle 66 for feeding paint from the reservoir into the cup or receptacle 62, whence the paint is removed by dipping the brush therein. This form of the device is adapted to be applied at the front or side of the user's body, and held 65 in position by means of a band or strap 67 mounted upon the back of the reservoir 63. The character 68 indicates a filler opening provided with a cap. It will be noted that the scraping edge 69 at the front of the brush cup is extended 70 forwardly of the front wall 70, so that the brush may be dipped into the cup without interference with the tank or reservoir.

In using the devices herein disclosed, the brush cup or receptacle which is fed through the con- 75

5 trol valve, is supplied with a limited amount of paint so that the possibility of spilling is reduced to a minimum. Ordinarily, the brush cup will contain paint or the like at a depth of an inch or less, the depth depending upon the size of the brush being used. The valve or stop cock may be opened either fully or partially to maintain a desired level of paint in the brush cup, or, 10 where a very thin paint is being used, the valve or stop cock may be opened at intervals to supply the amount of paint desired.

15 As stated hereinbefore, the brush cup or receptacle of Fig. 1 may be held in the hand instead of being attached to the painter's belt or clothing, and when used in that manner, the valve may be left open and the cup supplied with a desired amount of paint by merely elevating or lowering the cup relative to the level of paint in the reservoir.

20 The degree of flexibility of the tube or pipe 28 may be varied, if desired, so that by the use of a very substantial pipe or tube, the brush receptacle 22 may be sustained by the tube or pipe to a considerable extent. For example, by using a 25 tube or pipe 28 of copper or like material, the brush receptacle may be sustained entirely thereby, so as to eliminate the need for hooks such as 30 and 32.

25 It is to be understood that various modifications and changes may be made in the structural details of the device, within the scope of the appended claims, without departing from the spirit of the invention.

30 What is claimed is:

35 1. In a painter's apparatus, the combination of a fluid paint receptacle constituted of a standard paint can having a frictionally retained lid, and means for supporting said can with the lid applied thereto, in an inverted position upon the 40 person of the user of the apparatus, an adapter comprising a funnel shaped member having an upper annular flange, and means for securing said flange to the outer face of the lid, the lid being punctured within the area defined by the annular 45 flange of the adapter, a coupling means at the lower end of the funnel shaped member, a tube associated with said coupling means to convey fluid paint from the can through the punctured

lid thereof, and a paint brush receptacle connected with the tube for reception of fluid paint conveyed by the tube.

2. In a painter's apparatus, the combination of a fluid paint receptacle constituted of a standard paint can having a frictionally retained lid, and means for supporting said can with the lid applied thereto in an inverted position upon the person of the user of the apparatus, an adapter comprising a funnel shaped member having an 10 upper annular flange, and means for securing said flange to the outer face of the lid, the lid being punctured within the area defined by the annular flange of the adapter, a coupling means at the lower end of the funnel shaped member, a 15 tube associated with said coupling means to convey fluid paint from the can through the punctured lid thereof, a paint brush receptacle connected with the tube for reception of fluid paint conveyed by the tube, a fluid control valve inter- 20 posed between the tube and the receptacle, for obtaining a desired feed of fluid paint into the receptacle.

3. In a painter's apparatus, the combination of a fluid paint receptacle constituted of a standard paint can having a frictionally retained lid, and means for supporting said can with the lid applied thereto, in an inverted position upon the person of the user of the apparatus, an adapter comprising a funnel shaped member having an 25 upper annular flange, and means for securing said flange to the outer face of the lid, the lid being punctured within the area defined by the annular flange of the adapter, a coupling means at the lower end of the funnel shaped member, a 30 tube associated with said coupling means to convey fluid paint from the can through the punctured lid thereof, a paint brush receptacle connected with the tube for reception of fluid paint conveyed by the tube, a fluid control valve inter- 35 posed between the tube and the receptacle, for obtaining a desired feed of fluid paint into the receptacle, and means supporting the receptacle upon the person of the user at an elevation lower than the level of fluid in the reservoir, to establish 40 a gravity feed of fluid to the receptacle.

45 WILLIAM R. VAN WINKLE.
